UNITED STATES PATENT OFFICE.

LEONARD F. FULLER AND HAROLD F. ELLIOTT, OF PALO ALTO, CALIFORNIA, AS-SIGNORS, BY MESNE ASSIGNMENTS, TO FEDERAL TELEGRAPH COMPANY, OF SAN FRANCISCO, CALIFORNIA, A CORPORATION OF CALIFORNIA.

RADIOTELEGRAPHY TRANSMISSION SYSTEM.

Application filed May 22, 1919. Serial No. 298,909.

To all whom it may concern:

Be it known that we, LEONARD F. FULLER and HAROLD F. ELLIOTT, citizens of the United States, and residents of Palo Alto, county 5 of Santa Clara, and State of California, have invented a certain new and useful Radiotelegraphy Transmission System, of which the following is a specification.

The invention relates to radio telegraphy 10 transmission systems and particularly to a system employing an arc radio generator of the Poulsen type.

An object of the invention is to signal 15 without the use of the so-called compensating wave.

Another object of the invention is to provide 20 a signaling system in which the current in the antenna circuit is reduced to zero, without varying the load on the arc radio generator.

A further object of the invention is to provide 25 a signaling system in which the kilo-volt-amperes (Kva) which the signaling instrument must handle are reduced to a minimum.

The invention possesses other advantageous features, some of which, with the foregoing, will be set forth at length in the following description where we shall outline 30 in full those embodiments of the invention which we have selected for illustration in the drawings accompanying and forming part of the present specification. In said drawings we have shown several different forms 35 of our invention, but it is to be understood that we do not limit ourselves to such forms, since the invention, as expressed in the claims, may be embodied in a plurality of forms.

40 Referring to said drawings:

Figure 1 is a diagrammatic representation 45 of the system of our invention employing a double contact switching device.

Figure 2 is a similar representation of a modified form of the system.

Figure 3 is a similar representation of a modified form, showing a single contact switching device.

Figure 4 is a similar representation showing 50 a modified form of signaling device.

Figure 5 is a similar representation showing a modified form of circuit.

This invention provides for signaling

without the use of the compensating wave, by allowing current in the transmitting antenna only during the periods of dots and dashes and reducing the antenna current to zero during the intervening periods. The invention is characterized by the provision of a definite switching arrangement which 55 renders it impossible for the current to exist in the antenna when it is not desired, as contrasted with well known absorbing circuit methods, wherein current may be maintained in the antenna or switched into a local 60 absorbing circuit by reason of the special 65 and peculiar characteristics of the arc converter. In United States Patent No. 1,306, 223, issued to L. F. Fuller, an absorbing circuit system is shown. In the present system, 70 the peculiar characteristics of the arc are not relied upon and the antenna current is reduced from maximum to zero, by short circuiting the source of inphase E. M. F. in the circuit, and this is accomplished without 75 varying the load on the arc converter and consequently without varying the load on the D. C. generator feeding the arc. The 80 signaling device is inserted in the circuit at a point at which the power factor of the current and voltage is practically unity and consequently the load on the switching device is a minimum. One way in which it is possible to accomplish this result is by 85 locating a part of the circuit that replaces, during the periods of no radiation, the antenna circuit, directly in series with this 90 antenna circuit. This part of the circuit consists entirely of inductive and capacitive reactance neutralizing each other, or tuned 95 to the frequency of the system. Thus, the total effect of this part of the circuit on the antenna circuit is negligible and across the terminals of the inductance and capacity a minimum potential difference is obtained for 100 currents of the correct frequency. By proper arrangement of a resistance or other consumer of energy and a switching means, the substitute circuit can then be made to have substantially the same characteristics 105 as the antenna circuit, so that the load on the source remains the same, independent of choice of paths.

The system disclosed in Figure 1 comprises an arc converter 3 of the Poulsen 105 type which is fed with direct current from

the generator 1 through the combined magnet winding and choke coil 2, one side of the arc being grounded. Connected to the arc 3 is a circuit containing a variable radio frequency inductor 4, a radio frequency capacitance 5, a variable radio frequency resistor 6 and a suitable switch device. The switching device in this instance comprises two fixed contacts 10 and 11 and a movable contact 12 which is movable into engagement with either contacts 10 or 11. Contact 10 is connected to the circuit between the capacitance 5 and resistor 6 and contact 11 is connected to earth and to the earthed side of the arc. Movable contact 12 is connected to the resistor 6 and to the antenna circuit, comprising the variable radio frequency inductor 7 and the radiating antenna 8. When contacts 10 and 12 are in engagement, the arc oscillates on the antenna circuit, and when in this position, signals are transmitted. When contacts 11 and 12 are in engagement, the source of inphase E. M. F. is short circuited and no current exists in the antenna.

The resistor 6 is so adjusted that the radio frequency current delivered by the arc remains constant whether current is delivered to the antenna or circulates only in the local circuit. In practice, adjustments are made as follows,—contacts 11 and 12 are brought into engagement and the arc is allowed to oscillate on the local circuit. The inductor 4 is then varied to make the wave length of the local circuit equal to that which it is desired to radiate from the antenna. Contacts 10 and 12 are then brought into engagement, causing current to flow into the antenna, and inductor 7 is then varied until the chosen wave length is obtained.

The reading of the radiation ammeter 13 in the circuit is then noted and the local circuit is again closed. The resistor 6 is then varied until the reading of the ammeter is the same as when current was in the antenna. Signaling may now be accomplished by moving contact 12 alternately into engagement with contacts 10 and 11 without causing variation of the radio frequency current delivered by the arc, thereby imposing a constant load on the D. C. generator.

The reactive drop across the inductor 4 is equal and opposite to the reactive drop across the capacitance 5 and all the voltage that the switching device must handle is the inphase driving E. M. F. The product of current and volts at the switching device is a minimum and the power factor is unity. The circuit consisting of inductive reactance 4, capacitive reactance 5, and resistance 6, serves as a substitute during the period of no radiation for the antenna circuit; since by the adjustments it is made to have the

same characteristics as the antenna circuit, the choice of either circuit does not affect the load supplied by the system.

In the system shown in Figure 2, the contact 10 is directly connected to one side of the arc, and the circuit containing the inductor 4, capacitance 5 and the resistor 6, connects the same side of the arc with the antenna. By moving the key contact 12, the antenna may be directly connected to the arc, short-circuiting the inductor, capacitance and resistor, so that their losses do not reduce the antenna current. When the contacts 11 and 12 are in engagement, the source of inphase E. M. F. is short circuited through the resistor-inductor-capacitance circuit.

In the arrangement shown in Figure 3, the position of the resistor 6 in the circuit is changed occurring between the earthed arc electrode and the signaling key 14 which in this instance comprises only two contacts, 15—16. In this arrangement it is necessary to slightly detune the antenna circuit, i. e., when the arc is delivering current to the antenna, the wave length must be slightly different from that when it is oscillating on the local circuit only. This is necessary since otherwise the R I drop across the resistor 6 when the key is closed would produce an E. M. F. which would set up current in the antenna. By slightly detuning the antenna circuit, this "hangover" current is reduced to a minimum, because the frequency of the E. M. F. caused by the R I drop in the resistor is slightly different from the resonant frequency of the antenna. A resistor 17 of high resistance may be shunted around the key contacts to reduce sparking in the well known manner. Instead of employing a moving contact key for varying the resistance of the circuit to the radio frequency current, as shown in Fig. 3, a non-moving contact device may be used, such as is shown in Fig. 4. This device itself is described in the afore-mentioned Fuller patent and is known as a hysteresis key. When the polarizing D. C. circuit of the key 23 is open, the resistance of the local circuit is high and current flows in the antenna circuit. When the polarizing circuit is closed, the polarizing current causes a reduction in the resistance of the local circuit, so that current flows in it and not in the antenna. To accomplish this, the antenna circuit is slightly detuned, as set forth hereinbefore.

In Figure 5 we have shown a further modified arrangement of the system, in which short circulating is accomplished by a resonant circuit, consisting of the inductor 18 and the capacitance 19, of such values that the frequency remains the same whether the arc oscillates on the antenna or through the closed circuit. This short circuit may

be reduced by the detuning produced by varying the inductor 18. This may be accomplished by any of several well known methods, and we have chosen for illustration a key 21, short circuiting a few of the turns of the inductor 18.

The reason why current flows in the antenna circuit when the short circuiting resonant circuit is detuned is because the 10 LC product of inductor 4 and capacitance 5 is the same as that of the antenna circuit proper, consisting of inductor 7 and capacitance 8, and if inductor 4 and capacitance 5 are considered as forming a "frequency 15 sifter", then energy will arrive at point O, Figure 5, at this resonant frequency. The antenna circuit provides a resonant path for it, whereas the inductor-18-capacitance-19 path is non-resonant; hence the current 20 flows in the antenna. Still another way of considering the matter is that by means of the LC interposed next to the arc, the latter is made a source of constant frequency, like 25 a radio frequency alternator, thus with these connections the arc converter can deliver radio frequency energy in quantity only at the frequency set by the "frequency sifter".

We claim:

1. A radio telegraphy transmission system, comprising a source of radio frequency current, an antenna circuit, a circuit containing an inductor and capacity connecting the antenna circuit with one side of said source, and a signaling device connected to earth at the point of minimum voltage of the radio frequency system.

2. A radio telegraphy transmission system, comprising a source of radio frequency current, an antenna circuit, a local circuit containing inductance and a capacitance connecting the antenna circuit and said source and a signaling device arranged in the local circuit at a point of unity power factor.

45 3. A radio telegraphy transmission system, comprising a source of radio frequency current, a local circuit containing inductance and a capacitance connected to said source, an antenna connected to the local circuit so that the inductance and capacitance are interposed between one side of the source and the antenna, and means for closing and opening the circuit between the antenna and the other side of the source.

55 4. A radio telegraphy transmission system, comprising a source of radio frequency current, a local circuit containing inductance and a capacitance connected to said source, an antenna connected to said circuit, and means for closing said circuit whereby the source of inphase electromotive force of the antenna is short circuited and the antenna current reduced from maximum to zero, while maintaining the load on the said source substantially constant.

5. A radio telegraphy transmission system comprising a source of radio frequency current earthed on one side, a local circuit containing inductance and capacitance connected to said source on the unearthing side, 70 an antenna circuit connected to said local circuit so that said inductance and capacitance are interposed between the unearthing side of said source and the antenna circuit, and a switching device interposed between 75 the connection to the antenna circuit and the earthed side of the source.

6. A radio telegraphy transmission system comprising a source of radio frequency current, a load circuit, reactors connected in 80 series to the load circuit but having no appreciable effect upon the load supplied, an energy absorbing device so arranged that it may be connected in series to the reactors, and means for causing said device to be supplied with energy from the source through 85 the reactors, whereby the load current may be stopped.

7. A radio telegraphy transmission system comprising a source of radio frequency current, a load circuit, capacitive and inductive reactors connected in series with the load circuit, but so tuned that they have no appreciable effect upon the load supplied to the load circuit, an energy absorbing device arranged for series connection with the reactors, and means for causing said device to absorb energy from the source, whereby the load current is stopped, the device being so adjusted that the load supplied to it is substantially equal to that supplied to the useful 100 load.

8. A radio telegraphy transmission system comprising a source of radio frequency current, an antenna circuit, a local circuit having the same characteristics as the antenna circuit, that portion of the local circuit being in series with the antenna circuit which corresponds to the inductance and capacity of the antenna circuit, and means for rendering the remainder of the circuit active or inactive, whereby the antenna radiations may be stopped or continued.

9. A radio telegraphy transmission system comprising an arc radio generator having 115 one side earthed, an antenna, an inductance and a capacitance interposed between and connecting the antenna with the unearthing side of the generator, a conductor connected to the earthed side of the generator and forming with said inductance and capacitance a local circuit, a resistor in said circuit, and means for intermittently allowing current in antenna by opening and closing the local circuit.

10. In a radio telegraphy transmission system, means for producing radio frequency oscillations, a radiating circuit connected to the source, a local circuit having an inductance and a capacitance connected in series 130

with the source, the inductance and capacitance being substantially the equivalent of the inductance and capacitance of the radiating circuit, and means connecting between the radiating circuit and the local circuit for switching current into and out of the radiating circuit.

11. In a radio telegraphy transmission system, means for producing radio frequency oscillations, a radiating circuit connected to the source, a local circuit having an inductance and a capacitance connected in series with the source, the inductance and capacitance being substantially the equivalent of the inductance and capacitance of the radiating circuit, means connecting between the radiating circuit and the local circuit for switching current into and out of the radiating circuit, and means whereby the load on the source is maintained substantially constant for both active and inactive conditions of the radiating circuit.

12. In a radio frequency transmission system having a load circuit for radiating energy, means for producing high frequency oscillations connected to said circuit, means for causing the potential drop across two points in the load circuit to be a minimum for currents at a definite frequency, and a circuit across the two points.

13. In a radio frequency transmission system having a load circuit for radiating energy, elements arranged in series included in the load circuit so proportioned relatively

that there is a minimum potential difference between the two points corresponding to the terminals of the elements in series for currents having substantially the frequency which it is desired to use, and a circuit connected to these points.

14. In a radio frequency transmission system having a load circuit for radiating energy, means for producing high frequency oscillations connected to said circuit, means for causing the potential drop across two points in the load circuit to be a minimum for currents at a definite frequency, and a circuit having resistance connected across the two points.

15. In a radio frequency transmission system having a load circuit for radiating energy, elements arranged in series included in the load circuit so proportioned relatively that there is a minimum potential difference between the two points corresponding to the terminals of the elements in series for currents having substantially the frequency which it is desired to use, and a circuit having resistance connected across the two points.

In testimony whereof, we have hereunto set our hands at Palo Alto, California, this 13th day of May, 1919.
